INVENTOR,

B. B. BOWER,

UNITED STATES PATENT OFFICE.

BYRON B. BOWER, OF BAINBRIDGE, GEORGIA.

WATER-MOTOR.

SPECIFICATION forming part of Letters Patent No. 396,069, dated January 15, 1889.

Application filed September 24, 1887. Serial No. 250,608. (No model.)

To all whom it may concern:

Be it known that I, BYRON B. BOWER, a citizen of the United States, residing at Bainbridge, in the county of Decatur, Georgia, 5 have invented certain new and useful Improvements in Water-Motors, of which the following is a specification.

The object of my invention is to provide an improved apparatus for utilizing water-power 10 to drive machinery.

My invention consists in an improved organization of instrumentalities, whereby friction is reduced to a minimum, the maximum power of the water utilized, and the apparatus 15 rendered strong, durable, and reliable in every respect.

In the accompanying drawings, Figure 1 is a vertical central section of a water-motor embodying my invention; Fig. 2, a side view with 20 the casing in section.

In the drawings my invention is shown embodied in that class of motors in which an endless belt carrying buckets passes over pulleys within a suitable casing.

25 The pulleys A A' are arranged, respectively, at the bottom and top of the apparatus, the upper pulley being preferably located directly over the pulley A and a little above the water-level in the top of the penstock or water-supply. Any suitable frame-work may be used for supporting the pulleys. The upper pulley, A', is preferably mounted in adjustable bearings C, so that it may be raised and lowered to tighten or loosen the belt. The 30 lower pulley is inclosed in a casing, D, that closely surrounds it, and is provided with an entrance-port, a, and a discharge-port, b. Over the entrance-port is a column, E, that incloses one side of the bucket-carrying belt. When 35 the water enters the port a, it rises in the column E to about the water-level in the penstock. The column of water in the column E aids materially in effecting the rotation of the buckets, as a heavy pressure is thus afforded.

40 I have shown in the drawings a column, E', similar to the column E on the opposite side of the apparatus. This is simply for the purpose of adapting the apparatus to run in either direction, and may, if desired, be omitted.

45 At the entrance-port a, I preferably construct an antechamber, F, and in the bottom

thereof provide a waste-opening, F', having a valve, F², so that should any water be carried by the buckets beyond the discharge-opening b it will drain out. The valve under the entrance-port is of course closed when the apparatus is running.

55 The pulley A is provided on each side with annular sides g, that closely fit the edges of the buckets G, and may be flared a little at the outer edge, as shown, to readily admit the buckets. As the belt of buckets revolves around the pulley A, the edges of the buckets come in close proximity to the side rings, g, so as to form a water-tight joint, but not so 60 closely as to create undue friction. This arrangement prevents lateral pressure. Within the casing on each side I provide flanges h, arranged to closely fit against the annular sides g, just under the flared edge, to form water-tight joints, but with sufficient accuracy 65 to avoid friction. The flanges h are located opposite openings a, and are joined to the edges of the casing by offsets h', which fill up the openings that would otherwise occur at 70 these points. It is only necessary to have flanges upon one side of the apparatus—i. e., opposite the entrance-port—but I have shown two, as the drawings illustrate a duplex apparatus. The outer edges of the buckets come 75 in close proximity to the casing, so that the water does not pass by the buckets, but the buckets are carried with the water, thus obtaining the full power of the water-pressure.

80 A water-stop, X, is secured to the casing directly over the pulley A and extends down between the side rings, g, close to the periphery of the pulley A. The water-stop is preferably triangular in cross-section, as shown, and prevents the flow of water over the pulley and directs it into the buckets on their downward movement. The pulley A' is connected with a pulley, II, which may drive a belt, and thus communicate power to any desired point.

85 I claim as my invention—

90 1. The combination, substantially as set forth, of a casing, the upper and lower pulleys, the bucket-carrying belt, the buckets thereon, the side rings on the lower pulley, and the water-stop located over the lower pulley and 95 between the side rings.

2. The combination, substantially as set forth, of the upper and lower pulleys, the casing for the lower pulley completely inclosing it, except at the water-ports, the bucket-carrying belt, the buckets thereon, an entrance-port at the side of the casing, a discharge-port at the bottom of the casing and entrance-port on the opposite side of the apparatus and the drain-spouts, and valves located under the entrance-ports.

3. The combination, substantially as set forth, of the upper and lower pulleys, the cas-

ing for the lower pulley inclosing it and having an entrance-port at one side and a discharge-port at the bottom, the side rings on the lower pulley, and the water-stop over the pulley between the rings. 15

In testimony whereof I have hereunto subscribed my name.

BYRON B. BOWER.
